UNITED STATES PATENT OFFICE.

ARTHUR B. CLUNIES, OF ROCHESTER, NEW YORK, ASSIGNOR TO THE SILL
STOVE WORKS, OF SAME PLACE.

DESIGN FOR A FIRE-POT LINING-SECTION.

SPECIFICATION forming part of Design No. 31,198, dated July 11, 1899.

Application filed June 12, 1899. Serial No. 720,301. Term of patent 14 years.

To all whom it may concern:

Be it known that I, ARTHUR B. CLUNIES, a citizen of the United States, residing at Rochester, in the county of Monroe and State 5 of New York, have invented and produced a new and original Design for a Fire-Pot Lin-
ing-Section, of which the following is a speci-
fication, reference being had to the accom-
panying drawings, forming a part thereof.
o In the accompanying drawings, Figure 1 is
a front perspective view of a fire-pot lining-
section, showing my design; Fig. 2, a bottom
plan view of the same; Fig. 3, a rear perspec-
tive view, and Fig. 4 a vertical sectional view
5 on the line $x x$ of Fig. 2.

Similar reference-numerals indicate similar
parts.

As shown in the drawings, the leading or
material feature of the design is the shape
o and configuration of the lining-section. The
front face 1 of the section is concaved slightly
in the direction of the length, and the upper

end is slightly rounded, as at 2. At one end
is provided the plane face 3, and between it
and the face 1 is the angular surface 4, a simi- 25
lar angular face 5 being located between the
opposite end face 6 and the face 1.

The forward edge of the lower end of the
section is cut away on a curve substantially
the same as that of the front face 1, and ex- 30
tending rearwardly from the surface thus
formed are the two grooves 7, leaving the lands
8. The rear face 9 of the section is curved,
as shown, and at the lower portion is cut away
on a substantially straight line, forming the 35
shoulder 10.

I claim—

The design for a fire-pot lining-section sub-
stantially as herein shown and described.

ARTHUR B. CLUNIES.
